UNITED STATES PATENT OFFICE.

FRANK F. MACKEY, OF SEXSMITH, ALBERTA, CANADA.

MAIL-BOX SIGNAL.

1,334,106.

Specification of Letters Patent. Patented Mar. 16, 1920.

Application filed September 10, 1918. Serial No. 253,421.

To all whom it may concern:

Be it known that I, FRANK F. MACKEY, a subject of the King of Great Britain, residing at Sexsmith, in the Province of Alberta 5 and Dominion of Canada, have invented certain new and useful Improvements in Mail-Box Signals, of which the following is a specification.

This invention relates to signals and particularly to a signal for rural mail boxes 10 and has for its object to provide a simple, automatic and positively operated signal to be attached to a mail box for indicating to the postman collecting mail whenever there 15 is anything within the box to be collected, such means being operated by the weight of the mail matter deposited within the box to move a signal flag into display position.

With these objects in view, together with others which will appear as the description 20 proceeds, the invention resides in the novel formation, combination and arrangement of parts, all as will be described more fully hereinafter, particularly pointed out in the 25 claims, and illustrated in the accompanying drawings, in which:

Figure 1 is an end elevation of a rural mail box with the signal device applied thereto, and

Fig. 2 is a vertical, longitudinal sectional view of the same.

In the drawings, 5 indicates a mail box such as is used in the rural districts into which mail is deposited for collection by 35 carriers and which is fixed in position to be convenient both to the recipient of mail and to the postman. On the outside of the box at one end 6 is mounted a disk 7 on a central pivot 8 fixed to the box. Fastened to 40 the disk and projecting outwardly from the periphery thereof is an arm 9 carrying on its outer end a signal 10 which may be in the form of a flag, banner or of other shape and colored in a manner to attract attention. 45 Both arm and signal are preferably made of metal to withstand the weather.

Within the mail box 5 and above the bottom 11 of the box, is placed a movable bottom 12 hinged at 13 at the end of the box 50 opposite the disk 7 and extending toward the end 6 of the box, the movable bottom 12 being substantially as long and as wide as the interior of the box, sufficient space only being left between this bottom and the sides 55 and ends of the box to prevent contact therewith when the bottom is moved. Pro-

jecting from the free end of the bottom 12 is a pin 14 that extends through a vertical slot 15 in the end 6 of the mail box and has pivoted thereto one end of a link 16, 60 the opposite end of the link being pivoted by a crank pin 17 to the disk 7 so that movement of the bottom 12 will rotate or rock said disk.

When the mail box 5 is empty, the signal 65 10 will assume the position indicated in full line in Fig. 1, the parts being so adjusted that the weight of the signal will be slightly in excess of the weight of the bottom 12 so that when there is nothing in the 70 box, the signal will automatically rock into the position shown. When, however, any mail is deposited in the box through a suitable opening, not shown, it will fall upon the movable bottom 12 and the weight there- 75 of be sufficient to cause said bottom to fall, and through the connecting link 16, rock the disk 7 and the signal attached thereto into upright position, shown in dotted lines in Fig. 1. In this position, the postman 80 approaching, seeing the elevated signal will know that the box contains matter for collection which upon being removed, again shifts the preponderance of weight to the signal and the latter automatically drops. 85

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims, such for instance as substituting a crank arm for the disk 7 to the 90 outer end of which the crank pin 17 is attached and extending the signal support 9 95 inwardly to the arm.

Having thus fully described my invention, what I claim as new and desire to secure by Letters Patent, is:

1. The combination with a mail box, of a bottom pivoted at its rear end therein and having a pin projecting from its front end, an arm pivoted on the front end of the box 105 and carrying a signal, a crank pin connected with said arm, and a link connecting this pin with the pin on the bottom.
2. The combination with a mail box, of a movable bottom therein hinged at one end 110 to said mail box, and having a pin projecting from the opposite end through the ad-

jacent end of said box, a signal member pivoted to the latter end of the mail box, and a connection between said signal member and the pin projecting from the movable bottom for operating said member when a weight is placed upon the bottom.

3. The combination with a mail box, of a movable bottom therein hinged at one end near one end of the box, a pin projecting from the opposite end of said bottom through a slot in the adjacent end of the mail box, a disk pivoted to the latter end of the mail box and exteriorly thereof, a display signal projecting from the periphery of said disk, and a link between said disk and said pin for causing operation of the signal when mail matter is placed upon the movable bottom.

4. The combination with a mail box, of a movable bottom therein hinged at one end to one end of the mail box and extending to the opposite end, a pin projecting from the

latter end of said bottom through a vertical slot in the adjacent end of the mail box, a rocking disk pivoted to the latter end of said mail box and exterior thereof, a signal member projecting from the periphery of said disk, a link pivoted at one end to said pin and at its opposite end to said disk for moving the latter and so changing the position of the signal when a weight is placed upon or removed from said movable bottom, said signal being maintained by a slight preponderance of weight in a depressed position when the mail box is moved and to resume said position after being raised when all mail has been collected.

In testimony whereof I affix my signature in presence of two witnesses.

FRANK F. MACKEY.
